Primary Examiner — Rebecca Tsehay*(74) Attorney, Agent, or Firm* — Womble Bond Dickinson (US) LLP(57) **CLAIM**

The ornamental design for disposable vial with indent, as shown and described.

DESCRIPTION

FIG. 1 is a front/top perspective view of my disposable vial with indent;

FIG. 2 is a front elevation, the rear elevation is a mirror image thereof;

FIG. 3 is a right side elevation, the left side elevation is a mirror image thereof;

FIG. 4 is a top plan view thereof; and,

FIG. 5 is a bottom plan view thereof.

The oblique lines in the drawings indicate transparency.
